UNITED STATES PATENT OFFICE.

MICHAEL KIEFER, OF MUNICH, GERMANY.

CLAMP.

Application filed April 24, 1924, Serial No. 708,818, and in Germany May 2, 1923.

This invention relates to an improved clamp and particularly to a so-called edge-clamp, that is to say, a tool for clamping a piece of work from three sides including 5 an edge face thereof.

With this object in view the improved clamp comprises two lateral jaws acting in opposition to clamp the work therebetween, and a third jaw adapted to act in a direction perpendicular to that of the first stated 10 two jaws, in order to exert an end pressure on the edge face of the work gripped and clamped by the two first stated jaws.

I am aware that clamps of the kind are 15 old but the hitherto suggested clamps are objectionable for the reason that only the two lateral jaws are adapted to swing in and out whilst the third or intermediate jaw is stationary in this respect. This disadvantage results in that a reliable clamping 20 effect cannot be obtained at many a kind of work and the tool, in such a case, tends to slide off when overstrained to ensure a firm grip.

25 A further disadvantage of the clamps of the kind hitherto employed resides in the fact that two or more connecting joint bridges between the swinging jaws are indispensable, said bridges acting to impair 30 the required rigidity of the clamp so that the latter will get bent at any excessive clamping pressure. Moreover, the said joints or links involve inaccuracies in the 35 adjustment and fixation and the handling of the tool is very troublesome.

My improved clamp remedies all of the 40 said defects by the provision of jaws which, inclusive of the intermediate or third jaw, are adapted to swing or oscillate laterally, and further by the provision of a supplemental screw for the actuation of the two lateral jaws mounted on a common pivot 45 to turn thereabout.

In the accompanying drawing forming a 50 part of this specification a preferred form and manner in which the invention may be embodied and practised is shown by way of example.

In the drawing the two lateral swinging 55 arms or jaws are each constituted by two superposed angular members made of sheet steel and firmly united by means of bolts *a*. The one arm or jaw is shaped to form a double bell-crank lever *c*, *d* and adapted to turn about a pivot *b*, while the other arm or jaw *e* is shaped to form a bell-crank lever

likewise mounted to turn about said pivot *b* and provided with a lug *f*. In the end of the arm *d* a square block *g* is pivotally inserted between the two members constituting the jaw and a threaded spindle or screw *h* is pivotally connected with the said block *g*. Firmly connected or integral with the lug *f* is a nut *i* in which the screw *h* engages.

The common pivot *b* of the two jaws *c*, *d* and *e* is not stationary but mounted to turn freely. The middle portion thereof located intermediate the members forming the jaws is enlarged to form a collar *k* having a threaded opening for the reception of the 70 spindle or screw *l* of the third jaw *m* which is attached to the lower end of the screw *l* in a known manner by means of a ball and socket joint, as will be readily understood from the drawing.

In operation the two lateral jaws *c*, *d* and *e* are manually actuated by means of the spindle *h* to grip the work *n* and to hold it firmly between them, thus bringing the two jaws from the open position shown 80 in full lines to the clamping or closed position illustrated in dotted lines. If required, the intermediate jaw *m* may also be turned about its pivot and placed in front of the edge face of the work in order to engage 85 the same upon manually turning the spindle *l*. Thus the jaws of the clamp are adapted to be separately applied to the work which, as far as my knowledge goes, is not possible 90 in any of the hitherto known clamps.

As my improved clamp is of a very strong and durable construction a very high degree of compression can be obtained so that for this reason and owing to the separate adjustment and handling of the jaws the 95 latter can be accurately applied to the work and are prevented from sliding off.

While I have shown my invention embodied in a certain construction, it is not to be inferred that such construction represents the only form in which my invention may be embodied, but is illustrated and described only as illustrative of a form now preferred by me and to make clear the principle and the manner of the application of 100 my invention. I do not of course desire to be limited to the exact details of construction and arrangement shown and described as modifications are no doubt possible which will come within the scope of the invention. 110

What I claim is:

1. A clamp of the kind described, com-

prising in combination a pair of jaws pivoted on the same axis to swing towards and from each other, a third jaw also pivoted on said axis and extending between said pair, and means for swinging said third jaw and adjusting it radially with respect to said axis.

2. A clamp of the kind described, comprising in combination a pair of jaws pivoted on the same axis, a block also

pivoted on said axis having a threaded aperture extending substantially at a right angle to said axis, a threaded stem in said aperture, a clamping jaw carried by one end of said stem and a handle secured to the other end of said stem.

In testimony whereof I have hereunto affixed my signature.

MICHAEL KIEFER.
